UNITED STATES PATENT OFFICE

128,132

DESIGN FOR A FISHING ROD HANDLE

Vera Estelle Bell, Miami Beach, Fla.

Application April 19, 1941, Serial No. 100,529

Term of patent 14 years

To all whom it may concern:

Be it known that I, Vera E. Bell, a citizen of the United States, residing at Miami Beach, in the county of Dade and State of Florida, have invented a new, original, and ornamental Design for a Fishing Rod Handle, of which the following is a specification, reference being had to the accompanying drawing, forming part thereof.

I claim:

The ornamental design for a fishing rod handle, as shown.

VERA ESTELLE BELL.
